ABSTRACT OF THE DISCLOSURE

A switch mechanism for a cabinet having two doors, a carrier pivotally supported by the cabinet is moved into an operative position by the closing of one door. A switch, supported by the carrier, is actuated by closing of the other door only when the carrier is in said operative position. Thus, the switch is actuated only when both doors are closed.

Background of the invention

This invention relates generally to electrical switch mechanisms and, more specifically, to a switch mechanism particularly adapted for use with a cabinet having at least two doors wherein the switch will be actuated only upon closing of both doors.

A switch mechanism of the type involved herein is particularly useful with an automatic dishwasher wherein it is desirable, if not imperative, that the access opening be closed before the dishwasher is operated. The operation of an automatic dishwasher involves vigorous liquid spray action within the dishwasher. If the spray action is initiated when the dishwasher door is partially open, liquid will escape from the machine. There are, of course, other applications wherein it is desirable to prevent operation of a device until a closure for the device has been secured. Many devices have been proposed heretofore to provide such arrangement for a single door; however, these are generally inapplicable to an arrangement involving two or more doors, both of which must be closed before the device is operated. The present invention provides a simple structure requiring a single switch to assure that both doors of a two-door device are closed before the device is operated.

Summary of the invention

The present invention provides a switch mechanism, for use with a cabinet having first and second closure members, comprising a carrier movably supported by the cabinet, a switch supported by the carrier for movement therewith, means carried by the first closure member adapted to engage and move the carrier to an operative position upon closing of the first closure member, and means carried by the second closure member adapted to engage and actuate the switch upon closing of the second closure member only when the carrier is in the operative position.

Brief description of the drawing

While the specification concludes with claims particularly pointing out and distinctly claiming the subject matter which is regarded as the invention, it is believed the invention will be better understood from the following description of the preferred embodiment taken in connection with the accompanying drawing, in which:

FIGURE 1 is a fragmentary view, partially cut away to show details, of a dishwasher employing the present invention;

FIGURE 2 is a fragmentary sectional view taken along line 2—2 of FIGURE 1;

FIGURE 3 is a fragmentary sectional view taken along line 3—3 of FIGURE 1;

2

FIGURE 4 is a fragmentary sectional view taken along line 4—4 of FIGURE 1; and,

FIGURE 5 is a view similar to FIGURE 4 but showing the switch mechanism of the present invention in the condition it assumes when the doors are open.

Description of the preferred embodiment

Referring now to the drawing, and initially to FIGURE 1 thereof, there is illustrated an automatic dishwasher 10 having an outer cabinet 11 defining therein a wash chamber 12. Cabinet 11 has an open top and is provided with doors 13 and 14 to serve as closure members to close the open top. Door 13 is pivotal about a hinge 15 while door 14 is pivotal about a hinge 16 and each door may pivot, as shown in dashed lines in FIGURE 1, to an open position to allow access to wash chamber 12. It is anticipated that doors 13 and 14 will pivot through an angle of at least 90° and may pivot through an angle as large as 180° to reach the fully opened position.

A dish-supporting rack 17 is provided within wash chamber 12 to receive and support articles to be washed within dishwasher 10. Rack 17, and its supporting mechanism including a support 18 extending from one wall of cabinet 11, an arm 19 extending from door 14, and a link 20 pivotally interconnecting arm 19 and rack 17, are fully disclosed in application Ser. No. 458,269, filed May 24, 1965, now Patent No. 3,306,693, issued Feb. 28, 1967, by Melvin R. Kauffman which is assigned to the General Electric Company, assignee of the present invention. Because the rack system is fully disclosed in the aforesaid patent application, and because it does not form a material part of the present invention, it will not be described in detail herein.

Cabinet 11 has spaced walls 21 and 22 forming one side thereof and which define therebetween a compartment 23. The upper extremity of compartment 23 is defined by a top wall 24 which has therethrough a pair of openings 25 and 26. Opening 25 is adapted to receive, upon the closing of door 13, means in the form of an arm 27 projecting from door 13 toward cabinet 11. Similarly, opening 26 is adapted to receive, upon the closing of door 14, means in the form of an arm 28 projecting from door 14 toward cabinet 11. When doors 13 and 14 are fully closed, arms 27 and 28 project well into compartment 23 as illustrated in the drawing.

Referring now more particularly to FIGURES 2—5, there is illustrated a carrier 29 movably supported by wall 22 of cabinet 11 through a bracket 30 and pin 31. Bracket 30 is rigidly secured to wall 22 and pin 31 is carried by bracket 30. Carrier 29, in turn, is supported by pin 31 for pivotal movement thereabout. A spring 32 extends from bracket 30 to carrier 29 to bias carrier 29 to the position illustrated in FIGURE 5.

As can be seen from the drawing, pin 31 supports carrier 29 intermediate the ends of carrier 29. A switch 33 is secured to one end of carrier 29 to move therewith. Switch 33 may be a conventional micro-switch having a housing and an operator 34 extending therefrom. Switch 33 is actuated when operator 34 is depressed and may be of the normally open type, wherein depression of operator 34 closes the switch contacts, or may be of the normally closed type, wherein depression of operator 34 opens the switch contacts. A flexible member 35 is secured adjacent one of its ends to the housing of switch 33 and projects out beyond the distal end of operator 34. The term "flexible" as used herein is to indicate that member 35 is free to pivot relative to switch 33 but is substantially rigid throughout its free length whereby depression or flexing of member 35 anywhere along its length will effectuate depression of operator 34 thus actuating switch 33. The end of carrier 29 opposite the end to which switch 33 is

secured, is provided with a projecting element 36 having an inclined surface 37.

With the foregoing arrangement, closing of door 13 results in arm 27 engaging surface 37 of element 36. This engagement and subsequent complete closing of door 13 results in carrier 29 being pivoted about pin 31 from the position of FIGURE 5 to the position of FIGURE 4. Subsequent closing of door 14 causes arm 28 to engage member 35 thus depressing operator 34 and actuating switch 33. If door 14 is closed and door 13 remains open, arm 28 will not engage member 35 because carrier 29 will remain in the position of FIGURE 5. Also, if door 13 is closed while door 14 remains open, carrier 29 will be pivoted to the position of FIGURE 4; however, switch 33 will not be actuated due to the absence of arm 28 from compartment 23. Thus, the present invention provides a simple structure in the form of a switch mechanism which will not be actuated unless both doors of a two door cabinet structure are closed.

It should be noted that arms 27 and 28 travel an arcuate path as doors 13 and 14 pivot toward the closed position or the open position. Flexible member 35 is secured to the end of switch 33 facing toward the direction of approach of arm 28 so that arm 28, in effect, encounters an inclined surface to facilitate engagement between member 35 and arm 28 and depression of operator 34. For similar reasons, the width of arm 27 is sufficient to assure that the distal end of arm 27 first encounters inclined surface 37 rather than an edge of arm 27 encountering the side of element 36.

As will be evident from the foregoing description, certain aspects of the invention are not limited to the particular details of the construction of the example illustrated, and it is contemplated that various other modifications or applications will occur to those skilled in the art. It is therefore intended that the appended claims shall cover such modifications and applications as do not depart from the true spirit and scope of the invention.

What I claim as new and desire to secure by Letters Patent of the United States is:

1. A switch mechanism for use with a cabinet having first and second closure members comprising:

- (a) a carrier movably supported by said cabinet,
- (b) a switch including contacts and supported by said carrier for movement therewith,
- (c) means biasing said carrier away from an operating position,
- (d) means carried by said first closure member for engaging and moving said carrier to an operative position upon closing of said first closure member, and
- (e) means carried by said second closure member for engaging said switch and actuating said contacts upon closing of said second closure member only when said carrier is in said operative position.

2. The invention of claim 1 wherein said carrier comprises an elongated member pivotally secured intermediate its ends to said cabinet and said biasing means comprises a spring.

3. The invention of claim 1 wherein said means carried by said first closure member and said means carried by said second closure member each comprises an arm projecting from its respective closure member toward said cabinet.

4. The invention of claim 1 wherein said switch comprises a housing having an operator extending therefrom and a flexible member disposed over said operator whereby said means carried by said second closure member closes said contacts engaging said flexible member to depress said operator.
